BEACH BAG

Robert A. Jones, Los Angeles, Calif.

Application March 12, 1948, Serial No. 14,509

9 Claims. (Cl. 9—17)

1

My invention relates to hand bags, and more particularly to that type of hand bag which is known as a beach bag and which is adapted to carry bathing suits and like garments worn at a beach, together with bathing accessories, to and from a bathing beach. Such bags are well known and generally include at least a waterproof lining, whereby the wet towels and bathing suits are securely enclosed and the dress garments of the user are protected against wetting. Obviously, such hand bags may be used for other purposes than carrying of bathing gear, but are particularly adapted for such use.

With the foregoing in view, an object of my invention is to provide an improved beach bag.

A further object of the invention is to provide an improved beach bag which comprises a plurality of sections adapted to be detachably connected together by waterproof joints.

A further object is to provide an improved beach bag such as that last described which, when assembled, and emptied of the articles carried therein, provides a hollow waterproof receptacle which may be used as a float.

A further object is to provide an improved beach bag such as that last described, wherein a pair of end sections are detachably connected to a body section, and which end sections are adapted to be detachably connected together apart from the body section to provide an auxiliary hollow container of waterproof construction.

A further object is to provide an improved beach bag of hollow waterproof construction and which includes novel means for detachably connecting a carrying handle thereto.

A further object is to provide a novel combination of beach bag, float and beach ball.

Other objects and advantages reside in the particular structure of the invention, combination and arrangement of the several parts thereof, and will be readily understood by those skilled in the art upon reference to the attached drawings in connection with the following specification, wherein the invention is shown, described and claimed.

In the drawings:

Figure 1 is an elevation of a preferred form of the invention;

Figure 2 is an end elevation thereof;

Figure 3 is a longitudinal vertical section taken substantially on the plane of the line 3—3 of Figure 2;

Figure 4 is a transverse vertical section taken substantially on the plane of the line 4—4 of Figure 1;

2

Figure 5 is an elevation with parts broken away and shown in longitudinal vertical section and showing one use of the invention.

Referring specifically to the drawings, wherein like reference characters have been used throughout the several views to designate like parts, the beach bag according to the invention is of prolate form and comprises a body section 10 which is of hollow tubular construction and which may be made of any suitable rigid, semi-rigid, or flexible material of a waterproof nature. One surface of the body section 10 is formed with a pair of longitudinally-spaced, oppositely undercut recesses 11 which provide seats for the free ends of the legs 12 of a carrying handle 13. As is readily apparent from Figure 3, the legs 12 of the carrying handle are loaded for resilient movement in opposite directions away from each other, whereby the toes 14 thereof are resiliently seated in the undercuts of the recesses 11. At the same time, inward pressure in opposite directions on the legs 12 move them toward each other a distance sufficient to permit the toes 14 to clear the undercut parts of the recesses, whereby the carrying handle 13 may be readily detached from the body section 10. To provide a relatively smooth outer surface on the body section 10, it is preferred that the recesses 11 be formed in thickened portions defined by the inwardly-directed bosses 15 which extend into the interior of the body section 10. Likewise, the opposite ends of the body section 10 may be provided with inwardly-directed annular bosses 16, the free ends of which may extend axially outwardly of the ends of the body section, as indicated at 17 and 18, to provide flanges. It will be noted that the left-hand flange, Figure 3, is inset from the outer surface of the body section 10 and is formed with an exterior screw-thread. On the contrary, the flange 18 at the right-hand end of the body section provides a continuation of the outer surface of the body section and is formed with interior screw-threads. It should be noted that the screw-threads are complementary to each other. A sealing gasket 19 is detachably carried by the inset left-hand end flange 17 on the exterior thereof for a purpose which will be apparent later.

The bag according to the invention is completed by a pair of left and right end sections or closure caps 20 and 21, respectively. Each of the end sections is preferably formed with a pair of spaced recesses 22 providing finger grips. The left-hand end section or cap 20 is provided with an interior screw-thread complementary to the

thread of the flange 17, while the right-hand end cap 21 is provided with an inset flange 23, the exterior of which is screw-threaded to be complementary to the threads of the flange 18 of the body section. The right-hand end cap 21 has detachably secured on the exterior of the flange 23 thereof a sealing gasket 24. Such gasket 24 cooperates with the gasket 19 carried by the end flange 17 of the body section to provide a pair of waterproof joints when the end sections 20 and 21 are threadedly connected to the body section 10. The finger grip-providing recesses 22 in each of the end sections 20 and 21 are useful in screwing the end sections tightly onto the body section, whereby to form the waterproof joint aforesaid.

In view of the fact that the screw-threads of the end sections 20 and 21 are complementary to the threads of the body section which are in turn complementary to each other, it follows that the screw-threads of the end sections must be complementary to each other, whereby to permit them to be detachably connected together apart from the body section to provide the beach ball illustrated in Figure 5. As one of the sealing gaskets 24 is carried by the end section 21, such beach ball is waterproof when the two sections 20 and 21 are threadedly connected. When used as a beach ball, the finger grips 22 provide convenient means for handling the ball and likewise provide convenient grips for screwing the sections together and apart.

When the device is used as a float, the handle 13 may be detached and positioned inside the float, as illustrated in broken lines, Figure 3.

It follows from the foregoing that the device according to the invention is of a convenient shape for maximum capacity in use and, when not used for carrying beach articles or other goods, is capable of performing as a float either with or without the handle 13, and likewise is readily convertible into a beach ball for recreation purposes. While I have shown a particular means for connecting the sections together, it is obvious that other waterproof means might be substituted in lieu thereof.

Therefore, while I have shown and described what is now thought to be a preferred embodiment of the invention, it is understood that the same is susceptible of other forms and expressions. Consequently, I do not limit myself to the precise structure shown and described hereinabove except as hereinafter claimed.

I claim:

1. A beach bag, comprising a hollow cylindrical body of waterproof material, said body being open at each end, each end of said body including a substantially rigid ring, one ring being formed with an exterior screw-thread, the other ring being formed with a complementary interior screw-thread, a pair of hollow semi-spherical end sections each being formed with a screw-thread complementary to one of said threads of said rings and adapted to provide a threaded joint therewith, whereby to provide a prolate hollow container when said end sections are threaded onto said rings, means for sealing said joints, said body being formed to provide a pair of longitudinally-spaced undercut recesses therein, and a carrying handle detachably seated in said recesses.

2. A beach bag, comprising a rigid hollow cylindrical body section of waterproof material, each end of said section being open, one end being formed with exterior screw-threads, the other end

being formed with complementary interior screw-threads, a semi-spherical end section threaded on each end of said body section, sealing gaskets interposed between said body section and said end sections to provide waterproof joints, a carrying handle, and means detachably connecting said handle to said body section.

3. A beach bag, comprising a rigid hollow cylindrical body section of waterproof material, each end of said section being open, one end being formed with exterior screw-threads, the other end being formed with complementary interior screw-threads, a hollow rigid semi-spherical end section threaded on each end of said body section, sealing gaskets interposed between said body section and said end sections to provide waterproof joints, a carrying handle, and means detachably connecting said handle to said body section.

4. A beach bag, comprising a rigid hollow cylindrical body section of waterproof material, each end of said section being open, one end being formed with exterior screw-threads, the other end being formed with complementary interior screw-threads, a hollow rigid semi-spherical end section threaded on each end of said body section, sealing gaskets interposed between said body section and said end sections to provide waterproof joints, a carrying handle, and means detachably connecting said handle to said body section, and each end section being formed with spaced recesses therein providing finger grips.

5. A beach bag, comprising a hollow cylindrical body of waterproof material, said body being open at each end, each end of said body including a substantially rigid ring, one ring being formed with an exterior screw-thread, the other ring being formed with a complementary interior screw-thread, a pair of hollow semi-spherical end sections each being formed with a screw-thread complementary to one of said threads of said rings and adapted to provide a threaded joint therewith, whereby to provide a prolate hollow container when said end sections are threaded onto said rings, means for sealing said joints, said body being formed to provide a pair of longitudinally-spaced undercut recesses therein, a carrying handle detachably seated in said recesses, said threads of said end sections being complementary and being adapted to be threaded together apart from said body to provide a hollow beach ball.

6. A beach bag, comprising a hollow cylindrical body having open ends, one end being formed with an exterior screw-thread and the other end being formed with a complementary interior screw-thread, a sealing gasket carried by one of said ends, a pair of end caps, each end cap being formed with screw-threads complementary to said screw-threads of one of said ends, a sealing gasket carried by one of said end caps, and said end caps being adapted to be threaded on said ends of said body with said gaskets providing waterproof joints.

7. A beach bag, comprising a hollow cylindrical body having open ends, one end being formed with an exterior screw-thread and the other end being formed with a complementary interior screw-thread, a sealing gasket carried by one of said ends, a pair of hollow cup-shaped end caps, each end cap being formed with screw-threads complementary to said screw-threads of one of said ends, a sealing gasket carried by one of said end caps, said end caps being adapted to be threaded on said ends of said body with said gaskets providing waterproof joints, and said end

caps being adapted to be threadedly connected in opposed relation apart from said body to provide a waterproof auxiliary container.

8. A prolate beach bag of rigid hollow waterproof construction, comprising a tubular body section and a pair of semi-spherical end sections, means including waterproof joints detachably connecting said end sections to said body section, said body section being formed with a pair of spaced recesses therein, and means for detachably mounting a carrying handle in said recesses.

9. A prolate beach bag of rigid hollow waterproof construction, comprising a tubular body section and a pair of semi-spherical end sections, means including waterproof joints detachably connecting said end sections to said body section, said body section being formed with a pair of spaced recesses therein, means for detachably mounting a carrying handle in said recesses, and each end section being formed with at least one finger grip-providing recess. 15 20
